CLAIM

The ornamental design for a handle with timer, as shown and described.

DESCRIPTION

FIG. 1 is a front top-left perspective view of a handle with timer showing my new design;

FIG. 2 is a front elevational view thereof, the rear being substantially similar thereto but without the marker and
with different members;

FIG. 3 is a left side elevational view thereof;

FIG. 4 is a right side elevational view thereof; and

FIG. 5 is a front and top-left perspective view of a second embodiment of my new design, the other views being substantially similar to FIGS. 2-4.

FIG. 2.

FIG. 4.

FIG. 3.

FIG. 5.
